CLAIM

The ornamental design for a milk frother as shown and described.

DESCRIPTION

FIG. 1 is a front perspective view illustrating my design for a milk frother.

FIG. 2 is a front view thereof.

FIG. 3 is a right-side view thereof.

FIG. 4 is a rear view thereof.

FIG. 5 is a left-side view thereof.

FIG. 6 is a top view thereof.

FIG. 7 is a bottom view thereof.

FIG. 8 is a right-side view with the frother wand partially extended; and,

(Continued)

FIG. 9 is a rear view with the frother wand fully extended. The broken lines in FIGS. 1-9 show portions of the article that form no part of the claimed design.
